UNITED STATES PATENT OFFICE.

ANNA SHERBURNE AND ROGER HENRY VARICLE, OF LOS ANGELES, CALIFORNIA.

TOWEL-HOLDER.

1,276,125.

Specification of Letters Patent. Patented Aug. 20, 1918.

Application filed February 5, 1917. Serial No. 146,800.

To all whom it may concern:

Be it known that we, ANNA SHERBURNE and ROGER H. VARICLE, citizens of the United States, residing at Los Angeles, in 5 the county of Los Angeles, State of California, have invented certain new and useful Improvements in Towel-Holders; and we do hereby declare the following to be a full, clear, and exact description of the invention, 10 such as will enable others skilled in the art to which it appertains to make and use the same.

This invention relates to household devices and is directed more particularly to 15 holders adapted for suspending towels or similar articles.

An object of the present invention resides in the provision of a holder, adapted for attachment to a support, which may be 20 quickly and conveniently manipulated when applying or removing a towel.

A further object of the invention is to provide a towel holder embodying means of novel construction and arrangement for 25 readily clamping a towel.

With the above and other objects of similar nature in view, the invention consists in the construction, combination and arrangement of parts, set forth in and falling within 30 the scope of the appended claims.

In the drawing:

Figure 1 is a side elevation of our improved holder with a towel in position.

Fig. 2 is a transverse section taken on the 35 line 2—2 of Fig. 1.

Fig. 3 is a vertical longitudinal section through the device, and,

Fig. 4 is a similar section with the parts in position to release the towel.

40 Referring now more particularly to the accompanying drawing, the improved holder comprises generally speaking an attaching member 5, and relatively movable gripping elements 6 and 7 respectively. Specifically 45 the member 5 comprises a plate which is constructed preferably of metal and has struck outwardly therefrom spaced vertically aligned ears 8, the plate being further provided with openings 9 through which 50 suitable attaching means 10 are passed and driven into a support.

The upper of the ears 8 constitutes the support for the gripping element 6, while the lower thereof supports the element 7, 55 said elements being bifurcated at their inner ends as at 11 to receive the ears and being

pivotedly connected therewith through the medium of pins 12. The elements 6 and 7 are furthermore provided in their opposed faces each with a longitudinal channel 13 60 communicating with the related furcation 11, and a link 14 having its ends pivoted as at 15 in the forward portions of the channels and serving to connect the elements 6 and 7 for simultaneous movement. 65

The gripping element 6 presents much, the appearance of a downturned hook, the bill portion of which has its inner face 16 inclined downwardly and inwardly toward the plate 5, the free end of the element 7 70 being inclined as at 17 to parallel the face 16 and adapted to coöperate therewith in releasably clamping a towel. It will be noted that by inclining the coöperating gripping faces 16 and 17, that portions of a towel engaged 75 thereby will be crimped and frictionally clamped against detachment should an undue pull be exerted thereon.

In applying a towel to the holder, the element 6 is swung upwardly on its pivot 80 by means of a finger piece 18 formed at its free end, and such movement is communicated to the element 7 through the link 14, the pivoting of the elements eccentrically of each other serving to move the element 7 85 longitudinally of the element 6 so that the inclined faces 16 and 17 will be spaced apart and permit the insertion of a towel therebetween.

When released the elements will be returned by gravity and under the influence of the weight of the towel, to clamp the latter between the faces 16 and 17, the heavier the towel or the greater the downward pull exerted thereon, the firmer the towel 90 will be clamped, this by reason of the inclination of the gripping faces. 95

To release, the towel a slight upward and outward pull thereon will serve to again swing the elements upwardly and move the 100 faces 16 and 17 out of clamping relation; the towel being thus released and readily removable from the holder.

What is claimed is:

1. A holder of the character described, comprising a base, an upper hook shaped member pivoted to the base and forming a gripping jaw at its bill end, a lower member pivoted to the base and forming a jaw at its free end, to coöperate with the first named 110 jaw, a link connecting the members for differential movement to cause the jaws to move

toward and away from each other on shifting either member, and spring means active upon the lower member to hold the jaws together, the members being formed with inner channels to receive the link and spring.

2. A holder of the character described, comprising a base, an upper hook shaped member pivoted to the base and forming a gripping jaw at its bill end, a lower member pivoted to the base and forming a jaw at its free end to coöperate with the first named jaw, a link connecting the members for differential movement to cause the jaws to move toward and away from each other on

shifting either member, spring means active upon the lower member to hold the jaws together, the members being formed with inner channels to receive the link and spring, and ears on the base and forming the pivotal supports for the members and projected into the channels.

In testimony whereof, we affix our signatures in the presence of two witnesses.

ANNA SHERBURNE,
ROGER HENRY VARICLE.
